TRANSPARENCY PROJECTOR

Robert M. Simonelli, Palatine, Ill., assignor to
GAF Corporation, New York, N.Y.

Filed Jan. 30, 1974, Ser. No. 438,000

Term of patent 14 years

Int. Cl. D16—02

U.S. Cl. D61—1 J

FIG. 1

FIG. 2

FIG. 3

FIG. 4

FIG. 5

FIG. 6

FIG. 7

FIG. 8

FIG. 1 is a front perspective view of a transparency projector showing my new design;

FIG. 2 is a top plan view thereof;

FIG. 3 is a bottom plan view thereof;

FIG. 4 is a front elevational view thereof;

FIG. 5 is a right side elevational view thereof;

FIG. 6 is a left side elevational view thereof;

FIG. 7 is a rear elevational view thereof; and,

FIG. 8 is a rear perspective view thereof.

I claim:

The ornamental design for a transparency projector, substantially as shown.
